PIANO ACCORDION

Charles E. Barber, Chicago, Ill., assignor to Chicago Musical Instrument Company, Chicago, Ill., a corporation of Illinois

Application September 25, 1936, Serial No. 102,566

4 Claims. (Cl. 84—376)

This invention relates to piano accordions and more particularly to means for actuating the apertured slides which control the passage of air through the reed holders and thereby render operative or inoperative one or more sets of reeds in the bass mechanism.

Piano accordions of the character herein shown and described usually comprise five sets of reed holders in the bass mechanism, the sets of reeds being tuned to produce, respectively, (1) the lowest bass single tones, (2) intermediate bass single tones, (3) intermediate bass single and low "harmony" or accompaniment tones, (4) intermediate bass single and intermediate harmony tones, and (5) the highest bass single and harmony tones. Heretofore, slide members have been provided for rendering operative or inoperative only the two rows of reeds which are tuned for the lowest single bass tones and the intermediate bass single and low harmony tones, respectively. These slide members were operated simultaneously by actuating a single switch.

The main object of this invention is to provide additional switch mechanism and means for actuating, simultaneously or separately, two or more of the slide members which control the operativeness of the reeds in the bass mechanism. Another object is to provide actuating means for the purpose stated which are easily operable and conveniently located adjacent the bass key board.

In the drawings:—

Fig. 1 is a front elevation of the bass mechanism housing and button board.

Fig. 2 is a plan view of the bass mechanism, with the reed holders, bellows and bellows frame removed, showing the apertured slide members which control the passage of air through the reeds in the "open" position, i. e. with the apertures in register with the valve covered openings in the wall beneath the reeds.

Fig. 3 is a plan view of the bass mechanism shown in Fig. 2, showing the apertured slide members which control the passage of air through the reeds in the "closed" position, i. e. with the apertures not in register with the valve covered openings in the wall beneath the reeds.

Fig. 4 is a transverse vertical sectional view, partly in elevation, of the bass mechanism, taken in the plane of the line 4—4 of Fig. 2, but including the bellows and reed holders.

In that embodiment of the invention which I have chosen to illustrate in the drawings, the bass mechanism housing is indicated at 10 and the bellows at 11. The keyboard is provided with buttons 12 which actuate valves, not shown, lo-

cated below openings in the partition 13 beneath the reed holders 14, 15, 16, 17 and 18. The reeds of said holders 14, 15, 16, 17 and 18 are tuned to provide the tones heretofore described and designated 2, 1, 3, 4 and 5, respectively. The partition 13 is preferably made in three layers, the upper layer 19 being made of leather and the intermediate and lower layers 20 of metal. The rows of apertures which communicate with the reed holders 14, 15, 16, 17 and 18 are indicated at 21, 22, 23, 24 and 25, respectively.

In the present embodiment, the rows of apertures 22, 23 and 25 are opened or closed by apertured slide members 26, 27 and 28, respectively, mounted in the parts 20 of the partition 13. The apertures in the slide members 26, 27 and 28 are shown in register with the apertures 22, 23 and 25, respectively, in Fig. 2, thus rendering all the reeds operative. They are shown not in register in Fig. 3, whereby the reeds 15, 16 and 18 are rendered inoperative. The apertures 21 and 24 which communicate with the reed holders 14 and 17, respectively, in this embodiment, are not intended to be closed by slide members, as will be explained more fully hereinafter.

The means for actuating the slide members 26, 27 and 28 will now be described. A hinged switch comprising an elongated plate 29 is hinged at its upper edge to the housing 10 at 30, and has an inclined portion 31 in its lower portion which extends into the housing 10 through an elongated opening in the housing behind said switch plate 29—31. The switch plate 29 extends lengthwise between the bellows 11 and button board 12 and is accessible to the player at all times. The inwardly directed portion 31 of the hinge switch is pivotally connected at 32 to a rod 33, which extends transversely of the housing 10, and at its other end is connected to a slidably mounted plate 34. Said plate 34 has an upwardly directed pin 35 which extends through a slot 36 in the wall 37 and engages the forked end of a lever 38 pivotally mounted at 39 on a support 40. A coiled spring 41 is connected to the lever 38 and wall 37. The other forked end of the lever 38 engages a pin 42 on a slidably mounted plate 43 on which is pivotally mounted an inverted U-shaped member, the arms 44, 45 of which alternatively engage the arms 46, 47 of a lever 48 pivotally mounted on a support at 49. The lever 48 is pivotally connected at 50 by a link 51 to a lever 52. The lever 52 is pivotally connected at 53 to a support and at 54 to a double slide engaging member 55 having arms which engage the slides 26 and 27 as indicated at 56 55

and 57, respectively. The U-shaped member 44—45 is mounted on the plate 43 by a screw 58 which also retains in place a spring 59 which engages a pin 60 on the slidable plate 43, whereby the 5 arms 44 and 45 of the U-shaped member are normally centered. 61 is a spring secured at 62 to the housing 10 and bears on the pin 63 on the lever 52 to aid in retaining it in place.

When the hinged switch plate 29 is pressed inwardly, the rod 33 is moved transversely of the housing 10, and the plate 34 moves with it. The pin 35 on the plate 34, engaging one end of the lever 33, causes said lever to move about the pivotal connection 39, against the contractile 10 tendency of the spring 41. The pivotal movement of the lever 33 imparts a sliding movement to the plate 43 carrying the arms 44 and 45. Assuming the apertured slide members 26 and 27 to be in the "open" position shown in Fig. 2, the 15 arm 45 will contact with the arm 47 on the lever 48 when sliding movement is imparted to the plate 43 as just explained, and will cause the lever 48 and arms 47 and 48 to move about the pivotal connection 49, actuating the link 51, lever 20 52 and slide engaging member 55, thus moving the apertured slide members 26 and 27 to closed 25 position and all the parts between said slide members 26 and 27 and the pivoted lever 48 to the position shown in Fig. 3. The switch plate 29 is released by the player after being pressed inwardly as described, and upon such release the rod 33 and all parts between said rod 33 and the 30 plate 43 carrying the arms 44 and 45 return under influence of the spring 41 to the positions 35 shown in both Figs. 2 and 3, which are the positions of these parts at all times excepting when the switch 29 is being manually actuated. However, the lever 48 and the parts actuated by it are not affected by this return movement of the rod 40 48 and associated parts and said lever 48 and slide members 26 and 27 remain in closed position (Fig. 3) until the switch plate 29 is again actuated, whereupon the arm 44 engages the arm 46, causing the lever 48 to move on its pivot 45 49 and all the parts between said lever 48 and slide members 26 and 27 to move to the "open" position shown in Fig. 2.

A push switch actuates the slide member 28. Said switch comprises a bar or plate 64 rigidly connected to two push rods 65, 66, which extend through apertures 67 in the hinged switch plate 29 into bearing sleeves 68 in the housing 10. The push rod 65 is pivotally connected at 69 with a lever 70 pivotally mounted at 71 on a support. 50 The other end of the lever 70 is pivotally connected at 72 to a lever 73 pivotally mounted at 74 on a support. Said lever 73 is slotted at 75 for the reception of the pin 76 on the push rod 66. The other end of the lever 73 is pivotally connected at 77 to a slidable plate 78 which is 55 similar in construction to the plate 43 heretofore described. The plate 78 carries a pivotally mounted inverted U-shaped member having arms 79, 80, which alternatively contact with arms 81, 82 of a lever 83, pivotally mounted at 84 on a support. The lever 83 is pivotally connected at 85 by a link 86 to a lever 87. Said lever 87 is pivotally mounted at 88 on a support and is pivotally connected at 89 to a member 90 which is connected to the slide member 28. The U-shaped member 79—80 is mounted on the plate 78 by a screw 91 which also retains in place a spring 92 which engages a pin 93 on the slidable plate 78, whereby the arms 79 and 80 of the U-shaped member are centered. 94 is a spring secured at

95 to the housing 10 and bears on the pin 96 on the lever 87 to aid in retaining it in place. A spring 97 connected to the lever 73 and a fixed part such as the partition 13 or wall 31, retains the levers 70 and 73 in the normal positions 5 shown in the drawings.

When the push switch 64 is pressed inwardly, the levers 70 and 73 are moved about the pivots 71 and 74, respectively, and the ends pivotally connected at 72 are moved toward the adjacent housing wall 10. This action causes the lever 73, through the pivotal connection 71, to impart sliding movement to the plate 78 and arms 79, 80. If the apertured slide member 28 is then in the "open" position of Fig. 2, the actuation of the switch 64 will cause the arm 79 to contact with the arm 81 of the lever 83, moving said lever about the pivot 84, and causing the parts 86, 87, 90 and 28 to assume the "closed" position shown in Fig. 3. After the parts have assumed the position of Fig. 3, the next manipulation of the switch 64 causes the arm 82 of the lever 83 to contact the arm 80 and to move the slide 28 to the open position.

As soon as the switch 64 is released, the parts 25 between said levers 70, 73, and the arms 79 and 80 resume the normal position shown in both 30 Figs. 2 and 3, but the lever 83 and slide 28 and parts between them remain in either the open or closed position, resulting from the last manipulation of the switch, until the switch 64 is again manipulated.

The switches 29 and 64 are independently operable but may be actuated simultaneously or successively to move the apertured slide members 35 26, 27 and 28 to either open or closed positions, or to move the slides 26, 27 to open position and the slide 28 to closed position, or vice versa.

As heretofore stated, the reeds of the holder 40 14 in the present embodiment are tuned to produce intermediate bass single tones, the reeds of holder 15 are tuned to produce the lowest bass single tones, the reeds of holder 16 are tuned to produce intermediate bass single and low harmony tones, the reeds of holder 17 are tuned to produce intermediate bass single and intermediate harmony tones, and those of the holder 18 are tuned to produce the highest bass single and 45 harmony tones.

Assuming the parts to be in the positions 50 shown in Fig. 2, the apertures 21, 22, 23, 24 and 25 will be open and all the reeds available, providing "full accordion" tones at the command of the player. When the hinged switch 29 is actuated, the apertured slides 26 and 27 are moved to the closed position of Fig. 3, thereby cutting out the lowest bass single tones provided by reeds 15 and the intermediate bass single and low "harmony" or accompaniment tones provided by reeds 16, leaving available to the player the intermediate bass single tones provided by reeds 14, the intermediate bass single and intermediate harmony tones provided by reeds 17 and the highest bass single and highest harmony 60 tones provided by reeds 18.

Then, assuming the switch 29 is again actuated, the slides 26 and 27 will be moved from the closed position of Fig. 3 to the open position of Fig. 2. Assuming the switch 64 is actuated, the slide 28 will be moved from the open position of Fig. 2 to the closed position of Fig. 3. In this position of the apertured slides, the highest bass single and highest harmony tones, provided by reeds 18, will be cut out and all the other tones 75

provided by reeds 15, 14, 16 and 17 will be available to the player.

If the switch 29 is then actuated, while the parts previously moved to closed position by switch 64 are allowed to remain so, the apertured slides 26, 27 and 28 will all be in the closed positions shown in Fig. 3 and only the intermediate bass single tones provided by reeds 14 and the intermediate bass single and intermediate harmony tones of reeds 17 will be available to the player.

To restore the accordion to full bass single and harmony tones, both switches 29 and 64 may be simultaneously or successively manipulated, whereupon the parts will resume the positions shown in Fig. 2.

As heretofore stated, prior art constructions provided only one switch which actuated the slides for the reeds which correspond with the 20 reeds of the holders 15-16, but made no provision for actuating the slides which control the other reeds, for providing greater flexibility and variety in the available tones to be played. By the present invention, such flexibility and variety 25 are doubled without alteration of the size or form of housing used in prior art constructions.

The location, at opposite ends of the slides, of the operative means which connect the switch 29 with slides 26, 27, and the switch 64 with slide 28, is a feature of construction which permits the present improvement to be made without enlarging the conventional housing 10.

The construction of the switches 29 and 64 permits one or the other to be added to conventional accordions provided with one switch only, without substantial alteration of the existing structure.

Changes may be made in details of construction without departing from the scope of my invention and I do not intend to be limited to the exact form shown and described, except as set forth in the appended claims.

I claim:—

1. A piano accordion comprising a bass mechanism housing, a plurality of sets of reeds in the housing, parallel slidable members for controlling the passage of air through the reeds, a switch plate hingedly connected to the housing, a switch bar, a push rod rigidly connected to the switch bar and extending through an aper-

ture in the hinged plate, said push rod occupying a space forwardly of and within the surface area of the hinged plate, operative connections between the hinged plate and one end of a slid- 5 able member, and operative connections between the push rod and the opposite end of another slidable member.

2. A piano accordion comprising a bass mechanism housing, a plurality of sets of reeds in the housing, slidable members for controlling the 10 passage of air through the reeds, a switch plate hingedly connected to the housing, a switch bar, a push rod rigidly connected to the switch bar and extending through an aperture in the hinged plate, said push rod occupying a space forwardly of and within the surface area of the hinged 15 plate, and automatically reversible and non-automatically reversible operative connections between each switch and a slidable member for controlling the reeds. 20

3. In a piano accordion comprising a bass mechanism housing, a bellows connected to the housing, a bass mechanism keyboard, a plurality of sets of reeds in the housing and means for controlling the passage of air through said reeds, 25 manually operable switches connected to separate reed controlling means, one of said switches comprising an elongated plate hingedly connected to the housing between the keyboard and the bellows, and another of said switches comprising 30 a push bar rigidly connected to a push rod extending through the hinged plate, said push bar occupying a space forwardly of and within the surface area of the hinged plate. 35

4. In a piano accordion comprising a housing, 35 a keyboard, a plurality of sets of reeds in the housing, means for controlling the passage of air through said reeds, a pair of manually operable switches, and operative connections between each of said switches and said reed controlling 40 means, one of said switches comprising an elongated plate hingedly connected to the housing adjacent the keyboard, and another of said switches comprising a push bar rigidly connected to a push rod extending through the hinged 45 plate, said push bar occupying a space forwardly of and within the surface area of the hinged plate.

CHARLES E. BARBER. 50
